VEHICLE COMPRISING A PLURALITY OF SELECTIVELY DUMPABLE RECEPTACLES

Sam H. Killebrew, Auburndale, Fla.

Application July 30, 1957, Serial No. 675,098

18 Claims. (Cl. 298—8)

This invention relates to a bulk hauler.

An object of the invention is the provision of a bulk hauler, which is provided with unique individual dumping buckets used for the transportation of bulk fertilizers, lime, feed, and sand or other such bulk material.

Another object of the invention is the provision of means for allowing the operator to select the bucket to be dumped at will, merely by inserting a locking pin in the power shaft, as well as the bucket collar, thus temporarily locking the selected bucket to the shaft.

A further object of the invention is the provision of a mechanism that has a single permanently-positioned hydraulic piston, the thrust of which is transmitted by means of a fulcrum arm to a power shaft which extends the length of the body of the mechanism.

A still further object of this invention is the provision of a power shaft and locking pins, whereby the mechanism affords a bulk transport that is speedy in operation and is of unusual versatility.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention.

Figure 2 is an enlarged vertical sectional view taken on line 2—2, Figure 1, and looking in the direction of the arrows.

Figure 3 is an enlarged sectional view taken on line 3—3, Figure 1, looking in the direction of the arrows, and showing the bucket in a dumping position.

Figure 4 is a fragmentary enlarged top sectional view of the apparatus.

Figure 5 is an enlarged fragmentary view, partly shown in section, of the apparatus taken along line 5—5, Figure 4.

Figure 6 is a transverse sectional view taken on line 6—6, Figure 5, and looking in the direction of the arrows.

Figure 7 is an enlarged fragmentary top sectional view of a portion of the apparatus.

Figure 8 is an enlarged sectional view taken on line 8—8, Figure 2, and looking in the direction of the arrows.

Figure 9 is a fragmentary plan view of the chassis, showing the power pack units attached to the frame.

Figure 10 is a fragmentary view taken on line 10—10, Figure 2, and looking in the direction of the arrows.

Referring to the drawings by numerals, 1 designates the frame of the apparatus upon which is preferably mounted four buckets 2 (Fig. 1) that are provided to contain the material, irrespective of its nature, that is to be conveyed or hauled to the desired place of deposit.

Extending along, and to one side of the top portion

2

of each bucket 2 is a single hollow shaft 3 that is journaled in collars 4. These collars 4 are fixedly supported upon the upper end of standards 5 (Fig. 1). Each standard 5 is fastened at its lower end preferably to the side 5 of frame 1, additional angularly disposed standards 5A extend from each collar 4 to the opposite side of frame 1, as shown in Figure 1. In Figure 6 is shown the position of attachment of the collars 4 at the upper ends of the standards 5, and the relation of the shaft 3 to the buck- 10 ets 2.

For each bucket 2 there are two collars 6 located on the single hollow shaft 3. Securing and reinforcing plates 60 are secured to and extend between collars 6 and buckets 2. Two locking shafts 7 are provided for each bucket 2. The upper end of each shaft 7 is provided with a locking bolt-like pin 8 (Fig. 2) which is adapted to extend through registering apertures 6a and 3a in collars 6 and shaft 3, respectively (see Fig. 5). A fragmentary view of the bucket collar 6 is shown in Figure 5, as well as the locking pin 8 inserted through the bucket collar 6 and the shaft 3. When the bucket pin is thus inserted through the registering apertures 6a and 3a in the collars 6 and the shaft 3, this particular bucket is locked to the shaft and ready to be dumped. 20 The locking pins 8 inserted through the collars 6 are shown in Figure 7. The lower end of each locking shaft 7 is bent at right angles at 9, as shown in Figure 10. These ends 9 are placed in notched brackets 10, whereby the particular bucket 2 is locked against independent movement upon the rotatable hollow shaft 3. Each bucket unit is provided with this locking system, whereby any particular bucket can be operated for dumping, as the operator desires. When the locking means of each bucket is not in use, then the rotary shaft 2 may be 30 turning idle until the operator locks one or more of the buckets to shaft 3.

To rotate the shaft 3 a hydraulic cylinder 11 is provided from which a piston 12 extends. The cylinder 11 is suitably pivotally supported at 13 (Fig. 3) upon the frame 1. The piston 12 is connected at its outer end 14 to the arm 15, which arm is welded or otherwise permanently secured to the hollow shaft 3. A hollow hydraulic supply pipe 16 supplies the cylinder 11 with the power when the cylinder 11 is operated at the central 45 control 18 (Fig. 3) for swinging arm 15 and thereby dumping the contents of bucket 2. The enlarged top sectional view of this portion of the apparatus (Fig. 4) shows the cylinder 11 to be centrally located between the buckets 2. The central control 18 (Fig. 9) is in turn 50 connected with the power pack units 19, such units to be affixed to the frame 1.

When the bucket 2 is dumped (Fig. 3) the hinged cover section 17 of fixed cover 17A, which is hinged at 17C along the edges of the bucket adjacent shaft 3 will 55 swing open and allow the contents of the bucket 2, to be dumped, the outwardly swinging section 17 of the top acting as a guide for the passing of the material out of the bucket. Handle members 17B are provided on section 17A to facilitate manual dumping of the buckets when necessary or desirable.

When the power is removed from the cylinder 11, the bucket 2 will swing backwardly into position as shown in Figures 1 and 2. A section along lines 8—8 (Fig. 2) shows that when the buckets 2 are at rest, their bottoms 65 2', being of curved section (Fig. 8) extend below the top of the frame 1, thus lending rigidity and strength to the whole unit.

While I have described the preferred embodiment of this invention and illustrated the same in the accompanying drawings, certain minor changes or alterations may appear to one skilled in the art to which this invention

relates during the extensive manufacture of the same, and I, therefore, reserve the right to make such changes or alterations as shall fairly fall within the scope of the appended claims.

What I claim is:

1. A bulk hauling and dumping vehicle comprising an elongated generally horizontal frame, ground engaging wheels supporting said frame, said frame having spaced apart longitudinally extending side edges, a plurality of longitudinally spaced apart aligned uprights having their lower ends rigidly secured to said frame along one side edge thereof, a longitudinally extending unitary shaft journalled in the upper end portions of said uprights, power means mounted on said frame, a driving connection between said power means and said shaft for rotating said shaft, a plurality of buckets supported on said frame in longitudinally spaced apart relation, journal means for rotatably supporting said shaft rigidly mounted on the upper end portion of each of said buckets with said shaft extending through and journalled in each of said journal means, and means for independently releasably locking each of said journal means to said shaft to selectively connect each of said buckets to said shaft for rotation with said shaft from a position supported on said frame to an elevated dumping position above said shaft.

2. A device as claimed in claim 1 wherein said shaft is provided with a laterally extending arm rigidly secured thereto and said power means comprises a hydraulic cylinder and piston unit having one end pivotally connected to the extending end of said arm and the opposite end pivotally connected to said frame.

3. The structure of claim 1 wherein said power means includes a self contained power pack unit mounted on said frame.

4. The structure of claim 1 wherein the horizontal frame is open at its top and the bottoms of the buckets are downwardly convex to seat in the top opening of the frame to lend rigidity to the structure.

5. A device as claimed in claim 1 wherein the means for releasably locking said journal means to said shaft comprises a locking pin releasably inserted through said journal means and said shaft and a keeper on said bucket for retaining each of said locking pins in locking position.

6. The structure of claim 5 wherein each said keeper comprises a notched bracket fixed to the side of an individual bucket.

7. The structure of claim 6 where each locking pin is integral with the locking shaft, said shaft having an offset end engageable in the notch in said keeper.

8. A device as claimed in claim 1 wherein each of said buckets have a lid pivotally secured thereto on the side adjacent said shaft with said lid moving to open position with respect to said bucket under the influence of gravity upon rotation of said bucket to a dumping position.

9. The structure of claim 8 wherein the hinged lid covers only a portion of the top of the bucket, the remainder being closed by a fixed cover portion having a handle thereon.

10. A dumping vehicle comprising a generally horizontal frame, said frame having a side edge, vertically extending supporting means rigidly secured to said frame along said side edge thereof, a longitudinally extending unitary shaft journalled in said supporting means, power means mounted on said frame, a driving connection between said power means and said shaft for rotating said shaft, a receptacle, journal means for rotatably supporting said receptacle on said shaft, said journal means being rigidly mounted on said receptacle with the shaft extending through and journalled in said journal means, and means for releasably locking said receptacle to said shaft for rotation therewith.

11. A device as claimed in claim 10 wherein said shaft is provided with a laterally extending arm rigidly secured thereto and said power means comprises a hydraulic cylinder and piston unit having one end pivotally connected to the extending end of said arm and the opposite end pivotally connected to said frame.

12. The structure of claim 10 wherein said power means includes a self contained power pack unit mounted on the frame.

13. The structure of claim 10 wherein said vertically extending supporting means comprise a plurality of longitudinally spaced apart aligned uprights having their lower ends rigidly secured to the frame along said side edge thereof, and wherein a plurality of receptacles are provided, with means for independently releasably locking each receptacle to said shaft.

14. A device as claimed in claim 13 wherein the means for releasably locking each receptacle to said shaft comprises a locking pin releasably inserted through each said journal means and said shaft, and a keeper on each receptacle for retaining each of said locking pins in locking position.

15. The structure of claim 14 wherein each said keeper comprises a notched bracket fixed to the side of an individual receptacle.

16. The structure of claim 15 wherein each locking pin is integral with the locking shaft, said shaft having an offset end engageable in the notch in said keeper.

17. A device as claimed in claim 13 wherein each of said receptacles has a lid pivotally secured thereto on the side adjacent said shaft with said lid moving to open position with respect to said bucket under the influence of gravity upon rotation of said bucket to dumping position.

18. The structure of claim 17 wherein the lid pivotally secured to the receptacle covers only a portion of the top of the receptacle, the remainder being closed by a fixed cover portion having a handle thereon.
